LASTING MACHINE

Bernhardt Jorgensen, Marblehead, Mass., assignor to United Shoe Machinery Corporation, Flemington, N. J., a corporation of New Jersey

Application June 14, 1944, Serial No. 540,174

20 Claims. (Cl. 12—14)

This invention relates to lasting machines, and more particularly to toe-lasting machines having means for trimming the margin of the toe end of the upper materials. The invention is herein illustrated as applied to a machine constructed generally as disclosed in United States Letters Patent No. 2,324,509, granted on July 20, 1943, on an application of mine, but modified in certain respects in accordance with the further disclosures of Letters Patent No. 2,337,558, granted on December 28, 1943, and Letters Patent No. 2,377,887, granted on June 12, 1945, on other applications of mine. It is to be understood, however, that the invention is not limited to machine organizations of that particular character.

The above-mentioned machine is a fluid-operated machine provided with toe-embracing wipers which at a certain stage in the cycle of operations of the machine support the margin of the toe-end portion of the multi-ply upper in outspread position, with grippers which grip the margin of the upper and pull it outwardly over the wipers, and with upper-trimming means movable outwardly over the wipers to trim from the margin of the upper all but the outer layer of the upper materials, leaving the margin of the outer layer to be wiped inwardly over an insole on the last by the wipers. The upper-trimming means comprises a middle trimmer movable lengthwise of the last and a pair of side trimmers movable widthwise of the last to act on the upper prior to the action of the middle trimmer thereon. The grippers are so controlled as to release the upper substantially at the time when the side trimmers begin their trimming action thereon, whereupon all the grippers are moved farther outwardly to avoid interference with the trimmers.

An object of this invention is to afford better insurance that the margin of the outer layer of the upper will not be objectionably cut by any of the trimming knives. For this purpose, in the construction herein shown, the several trimmers carry with them members for positioning the margin of the upper flat on the wipers in advance of the edges of the trimming knives. These members are controlled by springs and are so positioned as to be moved yieldingly heightwise of the shoe relatively to the knives in response to pressure of the margin of the upper thereon, thus insuring their effectiveness to hold the upper pressed flat on the wipers as the knives are moved outwardly over it.

In order properly to control the waste material removed from the upper in the upper-trimming

operation, and thus to prevent it from falling into the machine and interfering with the working parts, the above-mentioned members for pressing the margin of the upper on the wipers are so arranged relatively to the trimming knives that the waste material is retained between them and the knives. After the upper-trimming operation the upper-trimming means is moved to carry the waste material to a discharge position, and the invention further provides means for gripping it in that position to effect its removal from the trimming means.

In the use of the machine to which the invention is herein shown as applied it may occasionally be desired, as more particularly herein-after explained, to operate on a shoe a second time from the beginning of the cycle of operations of the machine after the upper-trimming operation, at least, has been performed in a preceding cycle, or partial cycle, of operations. In order to insure that in that event the upper-trimming means will not damage the margin of the outer layer of the already trimmed upper, the invention still further provides means for preventing the upper-trimming means from moving into its normal relation to the shoe if the machine is thus used to operate on the shoe a second time.

The above and other features of the invention, including various novel details of construction and combinations of parts, will now be more particularly described with reference to the accompanying drawings and thereafter pointed out in the claims.

35 In the drawings,

Fig. 1 is a view partly in left-hand side elevation and partly in section of the upper portion of the machine to which the invention is shown as applied;

40 Fig. 2 is a plan view of a portion of the machine;

Fig. 3 is a section on the line III—III of Fig. 2;

Fig. 4 is a view in elevation from the front of the machine of the right-hand side trimmer and the parts associated therewith;

Fig. 5 is a section on the line V—V of Fig. 4, showing parts in elevation;

Fig. 6 is a view partly in elevation and partly in section, illustrating the relation of the side trimmer shown in Fig. 4 to the upper in the upper-trimming operation;

Fig. 7 is a vertical sectional view illustrating the action of the middle trimmer on the margin 55 of the upper;

Fig. 8 is a section on the line VIII—VIII of Fig. 7;

Fig. 9 shows a portion of the structure in elevation, as viewed in the direction of the arrow A in Fig. 7;

Fig. 10 is mainly a plan view, but with parts in section, illustrating the relation of the trimmers to the shoe at the end of the upper-trimming operation;

Fig. 11 is a view partly in plan and partly in section, illustrating the relation of the upper-trimming means to means shown at the left-hand side of Fig. 2 for removing the waste material therefrom;

Fig. 12 is a section on the line XII—XII of Fig. 11;

Fig. 13 is a section on the line XIII—XIII of Fig. 11; and

Fig. 14 is a section on the line XIV—XIV of Fig. 11.

In view of the disclosures in the previously mentioned Letters Patent, the present description will be confined to such portions of the machine as it is necessary to refer to for an understanding of this invention. For positioning the shoe bottom upward in the machine there is herein shown a member 2 arranged to engage the bottom of the forepart of the insole and having thereon a downwardly extending spur 4 (Fig. 10) arranged to enter a hole previously formed in the forepart of the insole, in accordance with the disclosure of Letters Patent No. 2,391,461, granted on December 25, 1945, on an application of mine. Side gages shown in said Letters Patent for further determining the position of the shoe with respect to lateral swinging movement about the axis of the spur 4 are, however, omitted, the side grippers (hereinafter referred to) being depended upon in their initial positions to determine with sufficient accuracy the position of the shoe in this respect. Early in the power operation of the machine the shoe is clamped against the member 2 by an upwardly movable toe rest 6. The shoe is presented with the out-turned margin of the toe end of the multi-ply upper between the open jaws of a plurality of grippers, comprising an end gripper 8 which grips the upper at the end of the toe and side grippers 10 which grip it at the sides of the toe, these grippers being mounted on a gripper support 12 (Fig. 1). Early in the cycle of operations of the machine the end gripper and the side grippers are moved respectively lengthwise and widthwise of the shoe to pull the upper, and while they are thus pulling the upper outwardly its toe-end portion is wiped heightwise of the last and is conformed to the contour of the last by upward movement of a substantially U-shaped flexible toe former 14 carried by a support 16. Also carried by the support 16 are toe-embracing wipers 18 located in a plane immediately above the toe former and arranged to support the margin of the upper on their top faces in outspread position. While the margin of the upper is thus supported a middle trimmer 20 and side trimmers 22 are moved respectively lengthwise and widthwise of the shoe in outward directions over the wipers to trim from the margin of the upper all but the outer layer of the upper materials, leaving the margin of the outer layer to be thereafter wiped inwardly over the insole by the wipers into position to be secured to the insole by cement applied to the shoe by means not herein shown in detail. In time relation to the outward movements of the trimmers, as the side trimmers be-

gin to act on the upper, the grippers are caused to release the upper and are moved farther outwardly to avoid interference with the trimmers, the grippers being shown in Fig. 10 in the positions which they occupy after such retractive movements. After the upper-trimming operation the upper is released by the toe former 14 and the operations of pulling it and of wiping it heightwise of the last are repeated, the grippers at this time acting only on the outer layer of the upper materials, as disclosed particularly in the previously mentioned Letters Patent No. 2,337,558. Cement is then applied to the shoe and the wipers 18 are operated to wipe the margin of the outer layer of the upper inwardly over the insole into position to be secured to the insole by the cement.

The trimmers 20 and 22 are supported on a carrier 24 by downward movement of which they are carried into positions to operate on the upper and by upward movement of which they are thereafter carried away from the shoe. The downward movement of the carrier is effected by fluid admitted at the proper time to a cylinder 26 (Fig. 3) and acting on a hollow post 28 to which the carrier is secured, the upper end of the post serving as a piston within the cylinder. The limit of the downward movement of the post and the carrier is adjustably determined by means fully disclosed in the previously mentioned Letters Patent No. 2,324,509. The upward movement of the post and the carrier is effected, in response to release of fluid from the cylinder 26, by a spring 30 in the post. As further fully disclosed in the last-mentioned Letters Patent, the post 28 is also mounted for turning movement to permit the carrier 24 to be swung laterally, and such swinging movement of the carrier toward the left is effected at the proper time after the upper-trimming operation to carry the upper-trimming means away from over the shoe and to bring into position over the shoe means above referred to for applying cement to the shoe, this cement-applying means being mounted on a support which is part of the carrier 24 and a portion of which is shown at 32 in Fig. 2. After such swinging movement of the carrier 24, it is again moved downwardly by fluid admitted to the cylinder 26 to carry the cement-applying means into position to apply cement to the shoe.

The middle trimmer 20 is provided with a knife 34 having a cutting edge curved widthwise of the shoe, and the side trimmers 22 are provided with knives 36 having cutting edges which in the construction herein shown are somewhat curved lengthwise of the shoe. The several knives, in operating on the upper, move in a plane parallel to the top faces of the wipers 18 with their cutting edges spaced from these faces a distance substantially equal to the thickness of the outer layer of the upper materials, so that they cut through the inner layer or layers of the upper materials on a line generally parallel to the edge of the insole while leaving the margin of the outer layer to be lasted inwardly over the insole. For convenience the drawings show only one layer of upper materials in addition to the outer layer, but it will be understood that ordinarily the toe end of the upper will include at least three layers. At the time of the upper-trimming operation the top faces of the wipers are positioned somewhat higher than the bottom face of the toe-end of the insole, as shown in Fig. 7, so that a small margin 75 of the trimmed layer or layers of the upper ma-

terials is left to be lasted inwardly over the extreme edge portion of the insole.

As further fully disclosed in Letters Patent No. 2,324,509, each side-trimming knife 36 is secured to a knife holder or carrier 38, and to impart trimming movements to these knives the two carriers 38 are moved along guideways 40 (Fig. 2) on the carrier 24, these guideways being curved about a vertical axis located opposite the end of the toe of the shoe in the upper-trimming operation. Such movements are imparted to the carriers 38 by a slide 42 (Fig. 3) movable lengthwise of the shoe along guideways on the carrier 24. The slide is moved in a rearward direction, i. e., toward the left in Fig. 3, thus to operate the side knives by a fluid-operated piston 44 movable upwardly in a cylinder 46 on the carrier 24 and connected by a link 48 to one arm of a three-armed lever 50 mounted on a rod 52 on the carrier 24, another arm of this lever being connected by a link 54 to a pin 56 on the slide 42. On the opposite sides of the slide 42 are cam faces 58 (Fig. 2) which serve in the movement of the slide to operate levers 60 connected by links 62 to the knife carriers 38. Also mounted on the carriers 38 are knives 64 arranged to sever from the rest of the upper materials the opposite ends of the strip of waste material produced by the action of the side knives 36 and the middle knife 34 in cutting the inner layer or layers of the upper materials on a line parallel to the edge of the shoe bottom. Pivotedly mounted on the above-mentioned pin 56 to swing in directions heightwise of the shoe is an arm 66 which serves as a carrier for the middle knife 34. The arm is held initially upraised by a spring 68 connected to it and to the slide 42, the limit of its upward movement being determined by engagement of a lug 70 on its rear end with the top of the slide. It will thus be seen that the arm 66 is carried rearwardly by the slide 42, but it remains upraised until the side knives 36 have been swung substantial distances away from each other in their operative trimming movements. The arm is then swung downwardly to carry the cutting edge of the knife 34 to the same plane as the cutting edges of the side knives 36, and by further movement of the slide 42 thereafter the knife 34 is moved rectilinearly to complete the upper-trimming operation begun by the side knives in their earlier action on the upper at the sides of the toe. The downward swinging movement is imparted to the arm 66 through a lever 72 pivotally mounted on a pin 74 on the carrier 24 and provided with a roll 76 arranged to engage an inclined face 78 formed on a plate 80 on the arm 66. Operative movement is imparted to the lever 72 by a roll 82 carried by one arm of the three-armed lever 50 and arranged to engage a cam face 84 on the lever 72. In the construction herein shown the plate 80 is adjustable lengthwise of the arm 66 and is held in adjusted position by screws 86 extending through slots in the plate.

For purposes of this invention the machine is provided with means affording better insurance that the margin of the upper, especially after its release by the grippers, will be positioned flat on the wipers in advance of the edges of the trimming knives to guard against any danger that the outer layer of the upper will be objectionably cut by the knives. Supported on the arm 66 of the middle trimmer 20 is a bar 88 (Figs. 3 and 7) on the lower end of which is secured a curved upper-engaging presser foot 90 arranged

to extend widthwise of the shoe substantially as far as the knife 34. At its upper end the bar 88 is pivotally mounted at 92 on one arm of a bell-crank lever 94 which is pivotally mounted on a pin 96 on the arm 66. The other arm of the bell-crank lever carries a screw 98 arranged to engage a stop face 100 on the arm 66. Mounted in a socket in the arm 66 is a spring-pressed plunger 102 in engagement with a finger 104 extending rearwardly from the upper end of the bar 88. It will thus be seen that the plunger 102 tends both to swing the bar 88 in a forward direction toward the arm 66 and also to move the bar bodily downward by swinging the bell-crank lever 94 about the pin 96, and that the screw 98 determines adjustably the limit of downward movement of the bar. Its forward swinging movement is limited by its engagement with a rear face 106 (Fig. 8) of a nut 108 which is threaded on a bolt 110 by means of which the knife 34 is secured to the arm 66, the nut and the bolt extending through a slot 112 in the bar 88. To assist in holding the bar 88 against lateral movement there is provided a stud 114 which is fast in the arm 66 and extends through a slot 116 in the bar. Preferably the bar is so adjusted that the lower face of the presser foot 90 is positioned initially in substantially the same plane as the cutting edge of the knife 34, and when the knife is moved rearwardly to perform the upper-trimming operation about the end of the toe the presser foot engages the upper materials just in advance of the edge of the knife and is forced slightly upward against the resistance of the spring plunger 102 by the pressure of the upper thereon. Throughout the rearward movement of the knife over the margin of the upper, therefore, the presser foot 90 continues to press yieldingly downward on the margin of the upper in advance of the edge of the knife to insure that the portion of the margin over which the knife travels will be held flat on the wipers. As the knife begins to cut the inner layer or layers of the upper materials the waste material severed by the knife is forced upwardly between the beveled edge portion of the knife and the presser foot 90, as illustrated in Fig. 7. In this operation the bar 88 may yield slightly in a rearward direction against the resistance of the spring plunger 102 in response to pressure of the waste material on the presser foot, and at the end of the upper-trimming operation the middle portion of the strip *w* of waste material removed from the upper remains clamped between the knife 34 and the presser foot.

Similarly, each of the side knife carriers 38 has supported thereon a bar 118 (Figs. 4, 5 and 6) the lower end of which is extended lengthwise of the edge of the shoe bottom for engagement with the margin of the upper in advance of the edge of the trimming knife 36 associated therewith. The bar 118 is secured by means of a rivet 120, a screw 122 and a dowel pin 124 to a holder 126 pivotally supported by a pin 128 on one end of a link 130 the other end of which is pivotally mounted on a pin 132 supported by a bracket 134 fast on the knife carrier 38. Mounted in a socket in the holder 126 is a spring 136 the upper end of which bears upwardly against the carrier 38 and the lower end of which is seated on a screw 138 threaded in the holder. The spring, therefore, tends to move the holder and the bar 118 in a downward direction and also to swing them about the pin 128 in a direction toward the trim-

ming knife 36. Downward movement of the holder and the bar is adjustably limited by engagement of a screw 140 in the bracket 134 with a shoulder 142 on the link 130. Swinging movement of the bar 118 toward the knife 36 is limited by its engagement with a flange 144 formed on a screw 146 by which the knife 36 is secured to the carrier 38. A socketed portion of the screw extending outwardly from the flange 144 lies in a slot 148 in the bar 118 to assist in preventing lateral movements of the bar. Similarly to the bar 88 associated with the middle knife, the bar 118 associated with each side knife is preferably so positioned by adjustment of the screw 140 that its upper-engaging face is positioned initially in substantially the same plane as the cutting edge of the knife 36, and the bar is forced slightly upward by pressure of the upper thereon just before the knife begins to cut the upper. Thereafter, during the outward movement of the knife over the margin of the upper the bar 118 serves to press the upper flat down on the wipers in advance of the edge of the knife, and at the same time the corresponding end portion of the strip of waste material is forced upwardly between the beveled edge portion of the knife and the bar 118, as illustrated in Fig. 6. In response to pressure of the waste material thereon the bar may yield slightly in an outward direction against the resistance of the spring 136 by swinging about the pin 128. At the end of the upper-trimming operation the opposite end portions of the strip of waste material are held clamped between the knives 36 and the bars 118 in the same manner as its intermediate portion is clamped between the knife 34 and the presser foot 90 on the bar 88.

As hereinbefore explained, after the upper-trimming operation the carrier 24 is moved upwardly to carry the trimming means away from the shoe, is swung toward the left to carry cement-applying means thereon to a position over the shoe, and is then moved downwardly to carry the cement-applying means into position to apply cement to the shoe. By the last-mentioned downward movement of the carrier the upper-trimming means is carried to a position within the upper portion of a waste receptacle 150 (Fig. 2) which corresponds to the waste receptacle 874 shown in Letters Patent No. 2,324,509. Mounted in this waste receptacle is mechanism different from that shown in the above-mentioned Letters Patent for removing the waste material from the trimming means. For purposes of this invention also a change has been made in the timing of the operation of the valve means whereby fluid is released from the cylinder 46 (Fig. 3), so that the trimmers 20 and 22 are maintained in the relation to one another which they occupy at the end of the upper-trimming operation (Fig. 10) until after they have been moved as above described to positions within the waste receptacle 150. From the disclosure of the last-mentioned Letters Patent it will be understood that this change in the timing is readily effected merely by adjustment of the valve-controlling means. Accordingly, the strip of waste material, clamped between the middle knife 34 and the presser foot 90 and between the side knives 36 and the members 118 as above described, arrives in the waste receptacle with substantial portions thereof exposed between the middle trimmer and the side trimmers. The above-mentioned mechanism in the waste receptacle for removing the waste material from the trimmers comprises means for

gripping it in these exposed locations and for holding it to effect its removal from the trimmers when the carrier 24 is moved upwardly away from the receptacle in its return to starting position. Secured within the upper portion of the receptacle is a casting 152 (Figs. 2 and 11) having oppositely extending wing portions 154, and mounted for adjustment along guideways on these wing portions are brackets 156 each having formed thereon an arm 158 which terminates in a jaw 160 arranged to engage one side of the strip *w* of waste material. Positioned above and below each bracket 156, respectively, are two arms 162 which are mounted to swing about a stud 164 extending through a bushing 166 (Fig. 14) in the bracket and are secured in fixed relation to each other to serve as a single arm. Secured to these two arms at corresponding ends of the latter is a jaw 168 arranged to clamp the strip of waste material against the jaw 160 in response to swinging movement of the pair of arms 162 about the stud 164. For thus swinging the jaws 168 from their initial positions (Fig. 2) to their waste-clamping positions (Fig. 11) there is provided a fluid-operated piston 170 movable in a cylinder 172 which is part of the casting 152. The piston is connected to the two pairs of arms 162 by a crossbar 174 and two links 176, the crossbar being pivotally mounted midway between its opposite ends on a pin 178 carried by the piston. It will be understood that when the carrier 24 is moved downwardly to carry the upper-trimming means into the receptacle 150, the strip of waste material is carried to a position between the jaws 160 and the jaws 168 associated therewith, the jaws 160 being properly positioned relatively to the waste material by adjustments of the brackets 156 relatively to the casting 152. The brackets are held in such adjusted positions by clamping screws 180 extending through slots 182 in the brackets into the wing portions 154 of the casting. After the waste material has thus been positioned between the jaws 160 and the jaws 168, the piston 170 is operated against the resistance of a pair of return springs 184, which are connected to the pin 178, by fluid admitted to the cylinder 172. Conveniently the admission of fluid to this cylinder may be controlled by the same valve whereby fluid is admitted to a cylinder (not herein shown) for imparting operative movements to the wipers 18, the construction being similar in this respect to that disclosed in Letters Patent No. 2,324,509. It will be understood that the jaws 160 and 168, by their hold on the strip of waste material, cause the strip to be withdrawn from between the trimming knives 34 and 36 and the strip-clamping members 90 and 118 associated therewith in response to the return upward movement of the carrier 24. Thereafter, upon release of the fluid from the cylinder 172, the springs 184 return the piston 170 and move the jaws 168 away from the jaws 160 to release the strip and permit it to drop in the receptacle 150, the limits of such return movements of the jaws 168 being determined by the engagement of pins 185 on the pairs of arms 162 with the brackets 156 (Fig. 2). Since the waste material, including a portion of the toe box, may have some adhesive matter incorporated therein, mechanism is further provided for insuring that the strip of material will be detached from the jaws 160 and 168. For thus detaching the material from the jaws 160 if it should adhere thereto, the lower one of each pair of arms 162 is extended to provide another arm 186 having fast on its end a waste-engaging

member 188. Since each arm 186 swings with the pair of arms 162 associated therewith, the members 188 are carried into positions to engage the waste material and to detach it from the jaws 160 as the jaws 168 are returned to their initial positions. To insure also that the waste material will be detached from the jaws 168 in case it should adhere thereto, there is associated with each of these jaws a member 190 which is secured to the corresponding bracket 156 and is arranged to engage the waste material in a location adjacent to the jaw 168 in response to return movement of the jaw.

In the use of the machine to which the invention is herein shown as applied it may occasionally be desired, because of some faulty condition observed immediately after the upper-trimming operation, to stop the machine and remove the shoe and thereafter to operate on it anew from the beginning of the cycle. In that case the machine may be stopped and may be made ready to begin a new cycle by the use of controlling means disclosed in Letters Patent No. 2,367,782, granted on January 23, 1945 on an application of mine. Occasionally, moreover, it may be necessary, even after completing the lasting of the toe end of the shoe, to detach the toe end of the upper from the insole and again to perform the toe-lasting operation on the shoe. In either case it is desirable that when the machine operates on the shoe the second time the upper-trimming means be prevented from moving into its normal position relatively to the toe end of the upper, in order to afford additional insurance that the margin of the outer layer of the already trimmed upper will not be damaged by the trimming knives. For this purpose the construction herein shown includes an arm 192 (Fig. 1) mounted to swing about a stud 194 on the frame from a normal idle position into position for its upper end 40 face to be engaged by a downwardly extending finger 196 on the carrier 24 at that time in the operation of the machine when the carrier is moved downwardly by fluid admitted to the cylinder 26 to carry the upper-trimming means toward the shoe. By the arm 192, therefore, the carrier is stopped short of the normal limit of its downward movement to cause the trimming knives to be positioned higher than usual at the time when they are operated. It will be understood that under those conditions the knives will receive idle movements without acting on the upper. For controlling the arm 192 the arm is connected by a link 198 to an arm 200 pivotally mounted on a pin 202 on the frame, and in fixed relation to the arm 200 is a forwardly extending operating arm 204 for use by the operator to swing the arm 192 into its operative position or to return it to idle position. Carried by the arm 204 is a spring-pressed pin 206 arranged to enter V-shaped notches 208 formed in a segment 210 on the frame to maintain the arm 192 in its different positions.

The manner of operation of the mechanisms provided for purposes of this invention having been fully explained in connection with the description of the construction of the mechanisms, no further description of the operation is necessary.

Having described the invention, what I claim as new and desire to secure by Letters Patent of the United States is:

1. In a lasting machine, the combination with wipers for wiping the margin of an upper about the toe end of a last inwardly over an insole on

the last, of a plurality of trimmers movable outwardly over the wipers in different directions respectively to trim from the margin of the upper all but the outer layer of the upper materials, the wipers being arranged to support the margin of the upper outspread in the upper-trimming operation, and members movable respectively with the different trimmers to position the margin of the upper outspread on the wipers in advance of the trimmers, said members being yieldingly movable each independently heightwise of the shoe in response to pressure of the margin of the upper thereon.

2. In a lasting machine, the combination with wipers for wiping the margin of an upper about the toe end of a last inwardly over an insole on the last, of a plurality of trimmers movable outwardly over the wipers in different directions respectively to trim from the margin of the upper all but the outer layer of the upper materials, the wipers being arranged to support the margin of the upper outspread in the upper-trimming operation, members associated respectively with the different trimmers and movable with them to position the margin of the upper outspread on the wipers in advance of the trimmers, and springs associated respectively with said different members for pressing them each independently against the margin of the upper on the wipers as they are moved outwardly over it.

3. In a lasting machine, the combination with wipers for wiping the margin of an upper about the toe end of a last inwardly over an insole on the last, of a plurality of trimmers comprising knives movable outwardly over the wipers in different directions respectively to trim from the margin of the upper all but the outer layer of the upper materials, the wipers being arranged to support the margin of the upper outspread in the upper-trimming operation, and members associated respectively with the different trimmers and movable with them to position the margin of the upper outspread on the wipers in advance of the edges of the knives, each of said members being yieldingly movable independently heightwise of the shoe relatively to the knife associated therewith in response to pressure of the margin of the upper thereon before the knife engages the upper to render the members effective to hold the margin of the upper pressed on the wipers as the knives are moved outwardly over it.

4. In a lasting machine, the combination with wipers for wiping the margin of an upper about the toe end of a last inwardly over an insole on the last, of a plurality of trimmers movable outwardly over the wipers in different directions respectively to trim from the margin of the upper all but the outer layer of the upper materials, the wipers being arranged to support the margin of the upper outspread in the upper-trimming operation, spring-controlled members associated respectively with the different trimmers and movable with them to press the margin of the upper yieldingly on the wipers in advance of the trimmers, and means for adjusting said members each independently in directions heightwise of the shoe relatively to the trimmers.

5. In a lasting machine, the combination with wipers for wiping the margin of an upper about the toe end of a last inwardly over an insole on the last, of a plurality of trimming knives comprising a middle knife movable lengthwise of the shoe and side knives movable widthwise of the shoe outwardly over the wipers to trim from the margin of the upper outspread on the wipers all

but the outer layer of the upper materials, carriers supporting said knives and movable with them, members also movable with the knives for engaging the margin of the upper and for positioning it flat on the wipers in advance of the knives, and supports for said members pivotally mounted on said carriers for movements heightwise of the shoe in response to pressure of the margin of the upper on the members.

6. In a lasting machine, the combination with wipers for wiping the margin of an upper about the toe end of a last inwardly over an insole on the last, of a plurality of trimming knives comprising a middle knife movable lengthwise of the shoe and side knives movable widthwise of the shoe outwardly over the wipers to trim from the margin of the upper outspread on the wipers all but the outer layer of the upper materials, carriers supporting said knives and movable with them, members also movable with the knives for pressing the margin of the upper outspread on the wipers in advance of the knives, supports for said members pivotally mounted on said carriers for movements heightwise of the shoe, and spring means arranged to control said supports and thereby to hold said members in pressure-applying relation to the margin of the upper as they are moved outwardly over it.

7. In a lasting machine, the combination with wipers for wiping the margin of an upper about the toe end of a last inwardly over an insole on the last, of a plurality of trimmers movable outwardly over the wipers in different directions respectively to trim from the margin of the upper outspread on the wipers all but the outer layer of the upper materials, and members associated respectively with the different trimmers and movable with them to position the margin of the upper outspread on the wipers in advance of the trimmers, said members and the trimmers being arranged to receive and to retain between them after the upper-trimming operation the waste material removed from the upper.

8. In a lasting machine, the combination with wipers for wiping the margin of an upper about the toe end of a last inwardly over an insole on the last, of a plurality of trimmers comprising knives movable outwardly over the wipers in different directions respectively to trim from the margin of the upper outspread on the wipers all but the outer layer of the upper materials, and members movable respectively with the different knives to position the margin of the upper outspread on the wipers in advance of the edges of the knives, each of said members being yieldingly movable heightwise of the shoe relatively to the knife associated therewith in response to pressure of the margin of the upper thereon before the knife engages the upper and being also yieldingly movable in an outward direction relatively to the knife to receive between it and the knife the waste material removed from the upper.

9. In a lasting machine, the combination with wipers for wiping the margin of an upper about the toe end of a last inwardly over an insole on the last, of a plurality of trimmers movable outwardly over the wipers in different directions respectively to trim from the margin of the upper outspread on the wipers all but the outer layer of the upper materials, and members associated respectively with the different trimmers and movable with them to position the margin of the upper outspread on the wipers in advance of the trimmers, said members and the trimmers being arranged to receive and to hold between them the

waste material removed from the upper and being movable to carry the waste material away from the shoe after the upper-trimming operation.

10. In a lasting machine, the combination with wipers for wiping the margin of an upper about the toe end of a last inwardly over an insole on the last, of a plurality of trimming knives comprising a middle knife movable lengthwise of the shoe and side knives movable widthwise of the shoe outwardly over the wipers to trim from the margin of the upper outspread on the wipers all but the outer layer of the upper materials, and members associated respectively with said different knives and movable with them to press the margin of the upper outspread on the wipers in advance of the knives, said knives and members being arranged to receive and to hold between them the waste material removed from the upper and being all movable as a unit after the upper-trimming operation to carry the waste material away from the shoe.

11. In a lasting machine, the combination with wipers for wiping the margin of an upper about the toe end of a last inwardly over an insole on the last, of a plurality of trimmers movable outwardly over the wipers in different directions respectively to trim from the margin of the upper outspread on the wipers all but the outer layer of the upper materials, members associated respectively with the different trimmers and movable with them to position the margin of the upper outspread on the wipers in advance of the trimmers, said members and trimmers being arranged to receive and to hold between them the waste material removed from the upper and being movable to carry the waste material to a discharge position and thereafter reversely movable, and means for gripping the waste material in said discharge position and for removing it from said members and trimmers in response to their reverse movement.

12. In a lasting machine, the combination with wipers for wiping the margin of an upper about the toe end of a last inwardly over an insole on the last, of a plurality of trimming knives comprising a middle knife movable lengthwise of the shoe and side knives movable widthwise of the shoe outwardly over the wipers to trim from the margin of the upper outspread on the wipers all but the outer layer of the upper materials, and members associated respectively with said different knives and movable with them to press the margin of the upper outspread on the wipers in advance of the knives, said knives and members being arranged to receive and to hold between them the waste material removed from the upper and being all movable as a unit after the upper-trimming operation to carry the waste material to a discharge position and thereafter reversely movable, and grippers arranged to grip in said discharge position portions of the waste material exposed between the middle knife and the side knives and to remove it from said knives and members in response to their reverse movement.

13. In a lasting machine, the combination with wipers for wiping the margin of an upper about the toe end of a last inwardly over an insole on the last, of upper-trimming means movable outwardly over the wipers to trim surplus material from the margin of the upper outspread on the wipers, said upper-trimming means having thereon means for retaining the surplus material removed from the upper and being movable to carry the surplus material to a discharge position, and means comprising jaws arranged

to grip the surplus material between them in said discharge position and to remove it from the upper-trimming means.

14. In a lasting machine, the combination with wipers for wiping the margin of an upper about the toe end of a last inwardly over an insole on the last, of upper-trimming means movable outwardly over the wipers to trim surplus material from the margin of the upper outspread on the wipers, said upper-trimming means having thereon means for retaining the surplus material removed from the upper and being movable to carry the surplus material to a discharge position and thereafter reversely movable, and means for gripping the surplus material in said discharge position and for removing it from the upper-trimming means in response to the reverse movement of the latter.

15. In a lasting machine, the combination with wipers for wiping the margin of an upper about the toe end of a last inwardly over an insole on the last, of a plurality of trimmers movable outwardly over the wipers in different directions respectively to trim surplus material from the margin of the upper outspread on the wipers, said trimmers having thereon means for retaining the surplus material removed from the upper and being movable to carry the surplus material to a discharge position and thereafter reversely movable, and means for gripping the surplus material in said discharge position and for removing it from said trimmers in response to their reverse movement.

16. In a lasting machine, the combination with wipers for wiping the margin of an upper about the toe end of a last inwardly over an insole on the last, of a plurality of trimmers movable outwardly over the wipers in different directions respectively to trim from the margin of the upper outspread on the wipers all but the outer layer of the upper materials, members associated respectively with the different trimmers and movable with them to position the margin of the upper outspread on the wipers in advance of the trimmers, said members and trimmers being arranged to receive and to hold between them the waste material removed from the upper and being movable to carry the waste material to a discharge position and thereafter reversely movable, jaws arranged to grip the waste material in said discharge position between them and to remove it from said members and trimmers in response to their reverse movement, said jaws being relatively movable thereafter to release the waste material, and means for engaging the waste material to insure its detachment from said jaws when it is thus released.

17. In a lasting machine, the combination with wipers for wiping the margin of an upper about the toe end of a last inwardly over an insole on the last, of upper-trimming means movable outwardly over the wipers to trim surplus material from the margin of the upper outspread on the wipers, said upper-trimming means having there-

on means for retaining the surplus material removed from the upper and being movable to carry the surplus material to a discharge position, means comprising jaws arranged to grip the surplus material between them in said discharge position and to remove it from the upper-trimming means, said jaws being thereafter relatively movable to release the surplus material, and means for engaging said material to insure its detachment from said jaws when it is thus released.

18. In a lasting machine, the combination with wipers for wiping the margin of an upper about the toe end of a last inwardly over an insole on the last, of upper-trimming means movable outwardly over the wipers to trim surplus material from the margin of the upper outspread on the wipers, said upper-trimming means having thereon means for retaining the surplus material removed from the upper and being movable to carry the surplus material to a discharge position, means including a pair of jaws arranged to grip the surplus material between them in said discharge position and to remove it from the upper-trimming means, one of said jaws being thereafter movable relatively to the other to release the surplus material, a member movable with said movable jaw for engaging the surplus material to insure its detachment from the other jaw, and additional means for engaging the material to insure its detachment from said movable jaw.

19. In a lasting machine, the combination with wipers for wiping the margin of an upper about the toe end of a last inwardly over an insole on the last in the course of a cycle of operations of the machine, of upper-trimming means movable outwardly over the wipers to trim from the margin of the upper outspread on the wipers all but the outer layer of the upper materials, a carrier supporting said upper-trimming means and movable heightwise of the shoe to carry said means into position thus to operate on the upper, and means for stopping said carrier short of its normal limit of movement in case the machine is used to operate on the same shoe a second time.

20. In a lasting machine, the combination with wipers for wiping the margin of an upper about the toe end of a last inwardly over an insole on the last in the course of a cycle of operations of the machine, of upper-trimming means movable outwardly over the wipers to trim from the margin of the upper outspread on the wipers all but the outer layer of the upper materials, a carrier supporting said upper-trimming means and movable heightwise of the shoe to carry said means into position thus to operate on the upper, and a member movable at the will of the operator into position to serve as an abutment to stop said carrier short of its normal limit of movement in case the machine is used to operate on the same shoe a second time.

BERNHARDT JORGENSEN.
